COKE OVEN

Josef Schäfer, Dortmund, Germany

Application August 8, 1939, Serial No. 289,060
In Germany August 23, 1938

2 Claims. (Cl. 202—145)

The invention relates to coke ovens having vertical heating flues in the walls between the heating chambers with regenerators connected thereto, one for each flue or for a group of flues, with horizontal or substantially horizontal air and gas distributing sole channels connected to the regenerators having also means of connection and to the stack of the oven. The distributing channels serve alternately for supplying air and fuel gas and for carrying away waste gas. The waste gas is hot, at a temperature which may be about 300° C., whereas, the temperture of the air and fuel gas may be only about 30° C., so that the gas volumes differ very considerably. That of the waste gas may be twice as great as that of the air and fuel gas. There are valves or dampers for regulating the flow of the gases to and from the regenerators, but in practice it is not possible to adjust the dampers at each reversal, so as to suit the inflow of air and gas and the outflow of waste gas alternately, and the general practice is to make only such adjustments as may be required to suit varying volumes of waste gas. The result is that the effective openings for the passage of gas are practically always much larger than is required for the admission of the air and fuel gas, so that regular distribution of the air and fuel gas to the regenerators is not obtained.

According to my invention this defect is overcome by subdividing the distributing sole channels by means of a horizontal partition having regulatable openings, the air and fuel gas being admitted to the lower sections of the channels, and the upper sections being in communication with the regenerators by means of the usual valve or damper controlled openings and having also a valve controlled outlet to the waste gas main. Each lower section may also have valve controlled communication with the waste gas main. With this arrangement the air and gas, before passing through the openings admitting them to the regenerators, pass through the regulatable openings in the horizontal partition, and these can be adjusted to suit the volume of air and gas, and secure proper distribution thereof, irrespective of the adjustment of the valves or dampers at the openings of the regenerators, these being adjusted as usual to suit the periodic outflow of waste gas.

An embodiment of the invention is shown in the accompanying drawing, in which:

Fig. 1 is a vertical section of such part of the oven as is required for illustrating the invention, the section being taken on the line E—F 55 of Fig. 3.

Fig. 2 is a cross-section on the line A—B of

Fig. 3 is a horizontal section on the line C—D of Fig. 1.

Each bank of vertical regenerators has below it two horizontal sole channels divided by a horizontal partition 2 into two sections, thus forming a pair of superposed sections *a*, *a*₁ on one side of the vertical dividing wall and a similar pair *b*, *b*₁ on the other side. The floors of the regenerators have openings 4, 5 controlled by dampers 6, for communication with the upper channel sections *a*, *b*, and the partition 2 has openings 7, 8, controlled by dampers 9, for communication with the lower channel sections *a*₁, *b*₁. The four channel sections *a*, *a*₁, *b*, *b*₁ communicate at each end by means of pipes 10 having valves 11 therein with a stack or waste gas flue 12 extending transversely of the banks of regenerators. The construction being the same at each end, only one end is shown in the drawing. A gas main 13 supplies fuel gas through pipes 14 with valves 14a to each lower section *a*₁, and air is supplied to each lower section *b*₁ through conduits 15 (Fig. 3). These air conduits have valves like the valves 14a of the gas conduits and may be connected thereby to an air main, like the gas conduits 14 are connected to the gas main 13. The openings 4, 7 and the openings 5, 8 are vertically in line with each other, and the roof of the passages 16 in the base of the oven is pierced with short shafts 17 vertically below the openings, so that a workman walking along the passages can have access to all the dampers, by means of a bar pushed through the walls.

What I claim as my invention and desire to secure by Letters Patent of the United States is:

1. A coke oven comprising a bank of vertical regenerators, two sole channels extending lengthwise of the bank below the same and arranged to collect and carry off waste gases from and to distribute fuel gas and air to said regenerators in alternate heating periods, horizontal partitions dividing said sole channels into upper and lower sections said upper channel sections communicating with said regenerators through regulable openings and said partitions having regulable openings therein for communication of said lower channel sections with said regenerators, valved means for supplying fuel gas to one and air to the other of said lower channel sections, a stack flue, and valved means for connecting both said sole channels to said stack flue.

2. A coke oven according to claim 1, in which the regulable openings in the regenerator floors and the regulable openings in the horizontal partitions of the sole channels are in vertical alignment.

JOSEF SCHÄFER.
